STEAM GENERATOR

Filed March 28, 1924

UNITED STATES PATENT OFFICE.

ELMER W. CLEVENGER AND JOHN PAUL WINE, OF STEPHENS CITY, VIRGINIA, AS
SIGNORS OF ONE-THIRD TO ORUM H. INGRAM, OF MARTINSBURG, WEST VIRGINIA.

STEAM GENERATOR.

Application filed March 28, 1924. Serial No. 702,654.

This invention relates to steam generators generally and more particularly to a water compartment adapted to be arranged adjacent and serve as a closure for the fire door 5 of a lime kiln or other furnace structure.

In the operation of lime kilns it is the present practice to provide a steam generator for supplying live steam to the ash pit of the kiln to assist combustion of the

10 fuel and maintain fuel economy. The kilns usually are provided with sheet iron or other thin metal doors which in operation soon become warped and cracked due to the intense heat within the kiln and must be discarded.

An important object of the present invention is to provide a water compartment adapted to serve as a closure for the fire door of a lime kiln or other furnace, the water 20 within the compartment being adapted to maintain a door temperature sufficiently low to prevent damage to the door from the heat of the fire box.

A further object is the provision of a device 25 of the above mentioned character which is adapted to generate steam by virtue of its proximity to the fire within the kiln, the steam being fed to the ash pit in the usual manner.

30 A further object is the provision of a device of the above mentioned character which is adapted to be moved to open the fire door to provide access to the fire box, novel means being employed for feeding water to the 35 water compartment and drawing steam therefrom without interfering with the movement of the door.

Other objects and advantages of the invention will be apparent during the course 40 of the following description.

In the drawings we have shown one embodiment of the invention. In this showing,

Figure 1 is a side elevation of a portion 45 of the device in place,

Figure 2 is a section on line 2-2 of Figure 1,

Figure 3 is a similar view on line 3-3 of Figure 2,

Figure 4 is a similar view on line 4-4 of 50 Figure 1,

Figure 5 is a detail perspective of the upper end of the door and associated elements,

Figure 6 is a section on line 6-6 of 55 Figure 1, and,

Figure 7 is a detail perspective of a modified form of piping connection.

Referring to the drawings the numeral 10 designates the front wall of a lime kiln or 60 other furnace structure having a fire door opening 11 and an ash pit door 12 of the usual construction whereby access is permitted to the fire box and ash pit. The wall 10 is provided upon opposite sides of the opening 65 11 with vertical guides 13 and a transverse stop 14 is arranged across the wall 10 beneath the lower limit of the opening 11 therein.

The numeral 15 designates the steam generator 70 as a whole comprising a hollow relatively flat metal receptacle divided by a vertical wall 16 to provide a water compartment 17 and a steam compartment 18. As shown in Figure 4 the compartment 18 is 75 arranged wholly outwardly of the opening 11 so that the fire within the fire box does not act directly upon the rear wall of the compartment 18. The generator 15 is provided upon opposite sides near the rear edges 80 thereof with vertical flanges 19 received within the guides 13 and adapted to reciprocate vertically therein. The stop 14 is adapted to engage the lower wall of the generator 15 when the latter is in its normal position 85 to limit the downward movement of the generator. The water compartment may be provided with a suitable gage glass 20 and the rear wall of the generator is preferably provided with spaced reinforcing members 90

21 adapted to assist in preventing the warping of the rear wall if the level of the water in the water compartment is not maintained at the proper point. The outer face of the generator 15 is provided on opposite sides 95 with racks 22 for a purpose to be described. A pair of bearings 23 are secured to the wall 10 of the kiln outwardly of the guides

13 and these bearings project beyond the outer face of the generator 15 as clearly shown in Figures 2 and 4. A transverse shaft 24 is mounted to revolve in the bearings 23 and is provided at one end with an operating crank 25. Pinions 26 are secured to the shaft 24 and adapted to mesh with the racks 22 as will be obvious.

Referring to Figure 3 of the drawings the 10 numeral 27 designates a vertical tube secured to the upper wall of the water compartment and depending to a point adjacent the bottom wall thereof. The tube 27 projects upwardly beyond the upper wall of 15 the water compartment and is provided at its upper end with a stuffing box 28 snugly receiving a stationary pipe 29 connected at its opposite end to a suitable source of water supply. As shown in Figure 3 the pipe 20 29 projects only a slight distance below the upper wall of the water compartment when the device is in normal position and the pipe is adapted to slide within the stuffing box 28 when the generator is moved upwardly. It 25 is obvious that the lower end of the tube 27 will feed water into the generator below the level of the water in the water compartment at all times so that condensation of steam above the surface of the water is minimized. 30 The steam compartment 18 is also provided with a depending tube 30 but this tube need not extend a substantial distance downwardly beyond the upper wall of the steam compartment. The tube 30 extends upwardly 35 beyond the generator and is provided at its upper end with a stuffing box 31 to slidably receive a stationary steam pipe 32, the lower end of which terminates at substantially the same horizontal level as the 40 lower end of the pipe 29. The pipes 29 and 32 extend vertically beyond the generator a sufficient distance to permit the generator to be moved upwardly to completely open the fire box. As shown in Figure 3 the pipe 45 32 is provided with a depending portion 33 which communicates as at 34 with the ash pit of the kiln. A steam pipe 35 is connected between the water compartment and the steam compartment as shown in Figures 50 3 and 6.

In Figure 7 of the drawings we have shown a modified form of external piping connection. In the modified form we provide a water supply pipe 36 in the form 55 of a flexible hose connected to the upper end of the tubular member 27 by a union 37 of the usual type. It will be obvious that similar flexible hose and union connections can be substituted in place of the pipe 32 60 and stuffing box 31.

The operation of the device is as follows:

Water is fed into the water compartment 65 through the pipe 29 and tube 27 to a level preferably near the top of the water com-

partment whereby the rear wall thereof will be maintained at a sufficiently low temperature to prevent damage thereto. Steam generated within the water compartment passes over into the steam compartment 18 70 through the pipe 35 from whence it passes through the pipe 32 into the ash pit of the kiln. The generator may be readily raised by revolving the handle 25 as will be obvious and when the generator is raised the lower 75 ends of the pipes 29 and 32 approach the bottom wall of the generator. Inasmuch as there is no water present in the steam compartment 18 the lower end of the pipe 32 may move downwardly to a point near the 80 bottom of the steam compartment without danger of water being blown through the pipe 32 into the ash pit. As previously stated, water fed into the water compartment will at all times pass below the surface of the water therein by virtue of the arrangement of the lower end of the tube 27.

The operation of the form of the device shown in Figure 7 is substantially the same 90 as in the form previously described. In the modified form, however, it will be obvious that the lower end of the hose 36 is rigidly secured to the upper end of the tubular member 27 and will reciprocate therewith, 95 reciprocation being permitted by virtue of the flexibility of the hose. As previously stated a flexible hose may also be substituted for the steam pipe 32.

It will be obvious that the device is adapted 100 for long service as a door for a lime kiln or other furnace structure by virtue of the cooling of the rear wall by the water. At the same time the heat of the kiln is utilized to generate steam to be fed 105 into the ash pit without the use of a separate generator thus effecting economy in operation.

It is to be understood that the form of 110 our invention herewith shown and described is to be taken as a preferred example of the same and that various changes in the shape, size, and arrangement of parts may be resorted to without departing from the spirit 115 of the invention or the scope of the subjoined claims.

Having described our invention, we claim:

1. A device of the character described comprising a pair of spaced guides adapted 120 to be arranged on opposite sides of the fire box opening of a furnace, a casing slidably mounted in said guides and divided transversely by a vertical wall to form water and steam compartments, said steam compartment being adapted to be arranged wholly 125 to one side of the fire box opening, a pipe communicating between the upper ends of said compartments, means for supplying water to said water compartment, and a 130

steam pipe connected to said steam compartments, means for supplying water to said water compartment, and a steam pipe connected to said steam compartment. 10

2. A device of the character described comprising an integral casing divided by a transverse vertical wall to form water and steam compartments, a pipe communicating between the upper ends of said compartments, means for supplying water to said water compartment, and a steam pipe connected to said steam compartment. In testimony whereof we affix our signatures.
